TURNTABLE BASE FOR TRUNKS

John Luft, Oshkosh, Wis., assignor to Oshkosh
Trunks and Luggage, Oshkosh, Wis., a corpora-
tion of Wisconsin

Application January 5, 1949, Serial No. 69,359

11 Claims. (Cl. 248—349)

1

This invention relates to a base which is swivelly connected with a trunk at its bottom to provide therefor a rotatable mounting upon which the trunk may also be rolled over a floor, platform, or other supporting surface. The base embodies in its construction certain novel features having to do with the rotatable mounting itself; also the trunk bottom is specially constructed to cooperate with the mounting and to assist in maintaining the trunk in perfect perpendicularity to the floor so that it may operate with the minimum of friction. Likewise protection is afforded for the turntable itself which is carried on the underside of the trunk bottom, and in which resiliency is embodied to a degree which will assist in maintaining the supported trunk vertically so as to have capacity for free rotation. My invention also includes in the turntable base a novel assembly of parts which contribute to its resiliency and strength, and also provide secure mountings for rollers by which to facilitate a rolling movement across the floor of the turntable with its supported trunk.

A primary objective which is reached by the present turntable base is (1) strength in a high degree so as to withstand all the abusive and rigorous treatment which is commonly encountered in use; (2) durability whereby the turntable base and parts associated therewith may be protected and safeguarded over an extended period of service; (3) lightness consistent with strength so as to avoid the addition of undue weight to the trunk; and (4) simplicity in the construction and assembly of the various parts whereby they may be put together quickly and easily, and, in case of need, be taken apart for purposes of adjustment, repair, or replacement.

A suggestive embodiment of my invention, as embodied in a turntable base for trunks such as will hereinafter be described in detail, is set forth in the accompanying drawing in the manner following:

Figure 1 is a bottom plan view of a trunk equipped with the present turntable base;

Fig. 2 is a vertical section through the base and lower portion of a trunk, taken on line 2—2 of Fig. 1;

Fig. 3 is a fragmentary horizontal section through the trunk, taken on line 3—3 of Fig. 2; and

Fig. 4 is an enlarged sectional detail of one of the supporting rollers in operative relation to the turntable.

For a clearer understanding of the present turntable base, I have shown the lower portion

2

of a wardrobe trunk comprising a bottom member 5 joined to two opposite side walls 6 and 7. The remaining two opposite sides of the trunk which are shown as open may be closed by doors 8 and 9 hinged at 10 and 11 to swing open about vertical axes. Flanges 12 may be built onto the free edges of each door as is common. Suitable protecting sheathing is usually applied exteriorly to the trunk at desired places, and also the usual fittings, such as a handle, locks, etc.

The turntable base, except for the parts which constitute its mounting, is positioned to the underside of the trunk bottom. As shown, it comprises upper and lower discs 15 and 16, respectively, having substantially the same diameter. The size of these discs is desirably such as to extend for the major distance crosswise of the trunk so as to afford a broad base therefor. For both discs plywood is an especially suitable material because of the properties of stiffness and resiliency with which it is endowed. The upper disc is perhaps $\frac{3}{8}$ " thick and the lower disc about $\frac{1}{4}$ " thick. Outside plies 17 of fiber or the like may be added to the lower disc for protective purposes, and a light steel plate 18 of circular form is desirably fitted over the top of the upper disc. The two plywood discs 15 and 16 together with the top plate 18 is herein sometimes referred to as "the disc assembly."

30 A relatively heavy thrust disc 20 is carried on the under side of the lower disc. As by means of a plurality of circularly arranged rivets 21, each of which extends through this disc and upwardly through the two plywood discs and the top plate 18, these several parts are secured immovably in permanently assembled relation. The two plywood discs 15 and 16 are maintained in slightly spaced relation through the interposition of circular flanges 23 each of which outstands laterally from a housing 25 wherein is confined a roller 26 bearing against a plurality of balls 27, the roller being adapted to rest upon the floor or other surface whereon the trunk is to be placed. Each roller housing is surmounted by a dome 28 of reduced diameter. To accommodate the several domes and housings, sockets of proper size are formed through the upper and lower discs 15 and 16, and the height of each dome is such that it extends for the full vertical distance of the associated socket so as to abut the steel plate 18 at the upper end thereof. At points proximate to each dome additional rivet fastenings 29 may be extended through the plate 18 and the two discs 15 and 16 to further strengthen the assembly 55 thereof.

The parts described up to this point constitute for the trunk a base which normally is stationary. Its depending rollers of which six is the indicated number provide a six point support for the base, and since these rollers are free to rotate in their mountings the base may readily be rolled over a smooth floor from one position to another. The disc-roller assembly which is disposed below the trunk is swively carried by its bottom, and provides for the trunk a rolling supporting base whereon it is sustained firmly and stably with capacity for rotation thereupon.

Affixed to the trunk bottom on its under side is a steel plate 32 which extends to a point close to each of its four sides. This plate also substantially overlies the top plate 18 of the disc assembly, but is centrally apertured so that the trunk bottom may not be unduly restrained from deflection. Associated with the plate 32 are four reinforcing slats 33 of hickory wood or the like, these slats at their mitered ends being enclosed within corner guards 34 of brass or the like. The dimensions of the panel defined by the four slats may be slightly less than the diameter of the disc assembly already described; to provide the necessary clearance for the discs each slat may be arcuately recessed at 35 upon its inner face, as shown. The periphery of the disc assembly may be protected and enhanced as to appearance by affixing thereto a circular angle strip 36 of brass or the like. Rivets 38 extending through the slats 33, plate 32, and trunk bottom may be used to interconnect these parts, supplemented by other rivets 39 which interconnect the trunk bottom and plate 32 at a point inwardly of the slats. Countersinking of the rivet heads is resorted to wherever it is desired to avoid protrusions.

The trunk bottom is provided at its center with a circular opening 41 therethrough. Over this opening is positioned a mounting disc 42 of heavy steel and of sufficiently large diameter to be anchored in place by rivets 43 which are extended therethrough and through the trunk bottom at a substantial distance away from its central opening. These rivets also extend through an annular block 44 of plywood or the like which is rested on the mounting disc 42, thereby anchoring the block 44 fixedly in place as well. The mounting disc separates one pair of complementary raceways 45 and 46, constituting a raceway unit which is disposed above the mounting disc, from a second pair of complementary raceways 47 and 48, constituting a second raceway unit which is disposed below the disc. Balls 49 within the raceway of each pair provide an anti-friction connection therebetween. The top and bottom raceways 45 and 48 which constitute thrust bearings are seated within opposing circular thrust blocks 51 and 52, respectively. Surrounding each raceway unit is an enclosing ring 57 by which its raceway components are maintained in assembled relation. The upper raceway unit is centered and held within the block 44 while the lower raceway unit is similarly centered and held within the trunk bottom opening 41.

A pivot bolt 60 having a head 61 at its lower end is extended vertically through the thrust disc 20, the disc assembly, the circular plate 18, and the raceway units, to afford a common axis therefor. The bolt head engages the thrust plate 20 at the bottom, and at its top the bolt is extended upwardly beyond the thrust block 51 where it is formed with screw threads to re-

ceive, in coacting relation therewith, a nut 62 which is desirably castellated. A cap 63 may surmount the bolt top and be affixed in place by screws which engage within threaded sockets formed in the top of the thrust block 51. These two parts alone, plus the annular block 44, protrude upwardly above the trunk bottom so as to occupy space within the trunk interior. A plywood cover 64 adjacent a partition 65 is shown as removably positioned over the block 44, but obviously the interior of the trunk may be subdivided or compartmented in any one of many different ways, so any further showing thereof is unnecessary.

Whenever the trunk is rotated upon its base, the ball raceways will minimize the friction. The top and bottom raceways 45 and 48, the two thrust blocks 51 and 52 wherein they are seated, and the disc assembly below the trunk bottom, constitute the unit which remains stationary; the intermediate raceways 46 and 47, together with the mounting disc 42 therebetween, and the trunk bottom 5 together with its body structure thereabove, constitute the unit which rotates about the pivot bolt 60 as an axis. An adequate support to prevent inclination of the trunk from the vertical is an important safeguard to satisfactory operation. This is provided by the strong support for the pivot bolt in the disc assembly below the trunk, and in the ample spread of the heavy mounting disc 42 which is clamped between the two raceway units and which is firmly anchored to the trunk bottom at points sufficiently radially distant to assure a continued vertical positioning of the trunk.

The clearance between the top plate 18 of the disc assembly and the annular plate 32 immediately thereabove need be but very little to provide for free rotation of the trunk upon its turntable base. At the same time, the distance of separation should be small so that, in case the trunk be poorly handled or be laterally pushed, no undue strain will be imposed upon the parts comprised in the turntable base. In any such event the disc assembly or the trunk bottom, or both, will be deflected out of a flat horizontal plane for the slight distance necessary to establish engagement between the disc top plate 18 and the trunk bottom plate 32 at one point. Further than this the deflection cannot proceed. Even while such engagement continues, rotation of the trunk may be effected in opposition to the light frictional contact between the two plates 18 and 32 whose confronting faces are smooth. When the lateral pressure against the trunk is relieved, the resiliency in the disc assembly and/or trunk bottom will restore the trunk to a normal position of verticality.

An important advantage in my turntable base is the accessibility afforded to its parts in case that repairs or adjustment should be needed. The cover 64 is first removed, the nut 62 is next unscrewed, and the pivot bolt is then freed for removal from the under side of the base which may thereupon be completely disconnected from the trunk. The thrust blocks and ball raceways are thereupon also freed for disassembly and removal. With all the vital parts thus exposed, any needed work can expeditiously be done with reassembly to follow in due course.

The disc assembly is also an important feature of this invention. The plies in each disc are desirably arranged with the grains crossing those in adjacent plies, and suitably adhered together, thereby to enhance the stiffness of the structure

and prevent warping. At the same time a disc so built up is susceptible of deflection at any time counter to a resistance which is always uniform, and the property of resiliency which is inherent in such a structure may be relied upon to restore the disc to its normal flat state. The use of two such discs facilitates the assembly and retention therewith of the several roller housings the lateral flanges whereof are disposed between the discs to fix the roller positions vertically thereof. The heavy plate 18 of steel or the like at the top of the upper disc 15 serves to reinforce the disc assembly; it also affords a strong and unyielding backing for the dome of each roller housing to oppose the up-thrust therefrom resulting from its sustenance of the imposed load of the entire trunk structure and its contents. At the bottom center of the lower disc 16 is affixed the steel plate 20 which receives the up-thrust from the head 61 of the pivot bolt. When the trunk is perfectly balanced upon its base, this bolt is subjected to little or no strain; but even under normal conditions of use it may be called upon occasionally to resist tension forces of considerable magnitude. When this occurs, the thrust plate 20 acts to absorb and distribute over an extended area the tension forces which would otherwise be localized to the possible damage of the lower disc 16. The mounting disc 42 upon the top of the trunk bottom 5 is likewise required to function similarly under these same conditions. By the means just described, I have adequately safeguarded and protected both the disc assembly and trunk bottom against any and all of such contingencies which may be encountered in the normal use of a wardrobe trunk which is mounted on the present turntable base.

The present turntable base is particularly useful with a trunk of the wardrobe type containing one or more compartments, partitions, drawers, clothes hanger supports, etc. Such a trunk is commonly "lived in" for weeks or months at a time. Besides being large and heavy, it is usually equipped with doors that are fitted to two or more of its sides. Complete accessibility requires that the trunk stand out from the walls of a room sufficiently to permit opening of any of its doors, and the placing of articles within, or removal from, the trunk as desired. In a small room, this may be difficult, if not impossible. With a turntable base as herein described, no trouble will be experienced in rotating the trunk to any desired rotative position; nor will there be any difficulty in rolling the trunk across the floor from one position to another, perhaps into a different room, whenever a change in location is desired.

I claim:

1. The combination of a bottom member with a center opening therethrough, a turntable base for supporting the bottom member comprising a disc positioned below the bottom member in closely spaced relation thereto, a ball raceway unit in connection with the bottom member and disposed above the same over the opening therethrough, a thrust bearing located above the bottom member in engagement with the raceway unit at the top thereof, spacer means extending between the raceway unit at the bottom thereof and the disc below the bottom member, and a pivot bolt in connection with the disc and extending therefrom axially and upwardly through the bottom member and raceway unit for connection with the thrust bearing for securing the turntable base to the bottom member.

2. A turntable base according to claim 1 in which the spacer means comprises a second raceway unit below the first and of uniform diameter therewith located within the opening of the bottom member, and a second thrust bearing underlying the second raceway unit.

3. A turntable base according to claim 1 in which a mounting plate is positioned between the raceway unit and the bottom member and fixedly secured to the latter, and in which the pivot bolt is passed through an opening in the mounting plate and extended between the disc at the bottom and the thrust bearing at the top.

4. A turntable base according to claim 1 in which a mounting plate is placed between the raceway unit and the bottom member, an annular block is located above the bottom member and surrounds the raceway and rests on the mounting plate, and means is extended through the block, plate and bottom member to anchor the block and plate fixedly thereto.

5. The combination of a bottom member with a center opening, a turntable base for the bottom member comprising a pair of superposed ball raceway units of uniform diameter, an apertured mounting plate between the two raceway units, a pair of opposed thrust bearings one in engagement with each raceway unit, the mounting plate, together with the associated raceways and bearings, constituting a unit adapted for installation upon the bottom member with the mounting plate resting upon the top face thereof and the lower raceway unit depending within its center opening, means for anchoring the mounting plate fixedly to the bottom member, a disc positioned below the bottom member in engagement with the bottom of the lower thrust bearing and thereby maintained in spaced relation to the bottom member, and a pivot bolt in connection with the disc and extended therefrom axially and upwardly for connection with the upper thrust bearing whereby to secure the turntable base to the bottom member for rotary movement thereof.

6. The combination of a bottom member formed with a center opening therein, a turntable base for the bottom member comprising dual raceway units of uniform diameter in superposed relation affixed to the bottom member and extending downwardly from the opening thereof, a pivot bolt in connection with the raceway units and extending downwardly therefrom, a disc unit carried by the pivot bolt below the bottom member in closely spaced relation thereto and in engagement with the lower raceway unit thereabove whereby to remain spaced from the bottom member for a predetermined distance, and means for reinforcing the bottom member comprising a plate affixed thereto and extending throughout a substantial area immediately above the marginal region of the disc unit to receive engagement therefrom in event of deflection of the turntable base from its normal plane.

7. A turntable base according to claim 6 in which the reinforcing means includes also a plurality of slats affixed to the bottom member and extending adjacent its periphery on all sides to the outside of the disc unit in close proximity and in partial overlapping relation thereto whereby to afford protection to the disc unit as well.

8. The combination of a resilient bottom member with a center opening, a turntable base for the bottom member comprising an apertured mounting plate and aligned raceway units of uniform diameter on opposite sides thereof in engagement therewith, spaced thrust bearings of

the same diameter as the raceway units wherein the outermost raceways are seated, a pivot bolt extending axially between the spaced thrust bearings and therebelow, and a disc unit fixedly carried by the pivot bolt below the bottom member in closely spaced relation thereto adapted to engage therewith at a point remote from the bolt axis in response to deflection of the bottom member out of its normal plane.

9. The combination of a bottom member with a central opening, a pair of superposed ball raceway units of uniform diameter, the lower raceway unit being located within the opening of the bottom member and the upper raceway unit being arranged above the bottom member, upper and lower thrust blocks wherein the raceways are seated, a disc assembly below the bottom member, and a pivot bolt in connection with the raceway units and extending downwardly therefrom and carrying at its lower portion the disc assembly, the top and bottom raceways, the two thrust blocks and the disc assembly below the bottom member rotatably supporting the bottom member.

10. The combination of a bottom member formed with a center opening therein, a turntable base for the bottom member comprising a raceway unit affixed to the bottom member and arranged within and extending downwardly from the opening thereof, a pivot bolt in connection with the raceway unit and extending downwardly therefrom, and a disc unit carried by the pivot bolt below the bottom member in closely spaced relation thereto and in engagement with the raceway unit arranged for rotation freely relative to the bottom member supported thereby, the disc unit comprising plural discs of plywood interconnected into a single unit, load-supporting

5. roller housings fitted into sockets formed in the lowermost disc, and a flange extended laterally from each housing and disposed upon the top face of the lowermost disc and in engagement with the bottom face of the disc immediately thereabove to secure the housing fixedly in place.

11. The combination of a bottom member formed with a center opening therein, a turntable base for the bottom member comprising a raceway unit affixed to the bottom member and arranged within and extending downwardly from the opening thereof, a pivot bolt in connection with the raceway unit and extending downwardly therefrom, a disc unit carried by the pivot bolt below the bottom member in closely spaced relation thereto and in engagement with the raceway unit arranged for rotation freely relative to the bottom member supported thereby, a plate fixedly secured on the top face of the disc unit, and load-supporting roller housings fitted into sockets extended through the disc unit to the plate at the top thereof, each housing engaging with the top plate to be backed thereby in sustaining the vertical load imposed by the supported bottom member.
